UNITED STATES PATENT OFFICE.

THOMAS W. HILL AND EUGENE J. REED, OF SWISSVALE, PENNSYLVANIA.

DESIGN FOR A REFRESHMENT STAND.

Application filed December 14, 1926. Serial No. 20,046. Term of patent 7 years.

To all whom it may concern:

Be it known that we, THOMAS W. HILL and EUGENE J. REED, citizens of the United States, residing at Swissvale, in the county of Allegheny and State of Pennsylvania, have invented a new, original, and ornamental Design for Refreshment Stands, of which the following is a specification, reference being had to the accompanying drawing, forming a part thereof.

In the drawings:

We claim:

The ornamental design for a refreshment stand, as shown.

In witness whereof, we have hereunto signed our names.

THOMAS W. HILL.
EUGENE J. REED.
